UNITED STATES PATENT OFFICE.

JOSEPH S. ISIDOR, OF NEWARK, NEW JERSEY, ASSIGNOR TO THE R. NEUMANN HARDWARE CO., A CORPORATION OF NEW JERSEY.

CATCH.

1,371,422.

Specification of Letters Patent. Patented Mar. 15, 1921.

Application filed January 29, 1920. Serial No. 354,989.

To all whom it may concern:

Be it known that I, JOSEPH S. ISIDOR, a citizen of the United States, residing at Newark, in the county of Essex and State 5 of New Jersey, have invented certain new and useful Improvements in Catches; and I do hereby declare the following to be a full, clear, and exact description of the invention, such as will enable others skilled 10 in the art to which it appertains to make and use the same, reference being had to the accompanying drawings, and to characters of reference marked thereon, which form a part of this specification.

15 This invention has reference, generally, to locking devices adapted for use with the pockets and flaps of kit-boxes, brief-cases, and also with suit-cases and bags of the various kinds; and, the present invention 20 relates, more particularly, to a novel catch- construction for the pockets and flaps of bags and kit, or lunch-boxes, as well as suit- cases of the various kinds, the main mem- bers of the catch being usually stamped out 25 of sheet-metal, as brass, or the like.

It has been found in practice, that with the usual construction and arrangement of the various devices and parts of catches such as hereinafter described, comprising 30 an upper and a lower main body-member, the lower main body-member being provided with a sheet-metal box to which is pivotally secured the usual lifting or raising member or lever for bringing the yoke-portion 35 of the usual holding or retaining loop which is also pivotally connected with said lifting or raising member or lever, that on account of the sheet-metal structure of the said box, and the necessary pivotal disposi- 40 tion of the lifting or raising lever and of its holding or retaining loop, and of the disposition of the outer face of the box, as at present made, when the lifting or rais- 45 ing member or lever is raised by the oper- ator, unless the latter is most careful, the said lever will be forced back too far, where- 50 by the pivotally connected members, being made of sheet-metal, are almost immediately jammed and forced out of their operative engagement, so as to either break the catch at the point of pivotal connection between the said lifting or raising lever and the box,

or by jamming the parts, rendering the catch completely inoperative.

With the above in view, the present in- 55 vention has for its principal object to pro- vide a sheet-metal catch of the general ar- rangement and construction of parts, as hereinafter more fully set forth, in which the outer face of the box to which the lift- 60 ing or raising member or lever is pivotally attached, is inclined in the manner shown in the accompanying drawings, and as herein- 65 after described, and whereby the lifting or raising member or lever can be fully oper- ated without producing or causing any dis- 70 turbed or broken relation of the pivotally connected parts of the catch.

Other objects of the present invention not at this time more particularly enumerated 70 will be clearly understood from the follow- ing detailed description of the present in- 75 vention.

With the various objects of the invention in view, the said invention consists, prima- 75 rily, in the novel catch hereinafter more fully set forth in the following specification and then finally embodied in the clauses of the claims which are appended to the said 80 specification.

The invention is clearly illustrated in the accompanying drawings in which:—

Figures 1 and 2 are a front and side-edge view respectively, of a catch made according to and embodying the principles of the pres- 85 ent invention, the various members of the catch being represented in their locked en- gagement.

Fig. 3 is a side-edge view of the catch, showing the several parts of the catch in 90 their disengaged or unlocked relation; and Fig. 4 is a transverse vertical sectional rep- 95 resentation of the catch, said section being taken on line 4—4 in said Fig. 1.

Similar characters of reference are em- 95 ployed in all of the said above described views, to indicate corresponding parts.

Referring now to the several figures of the drawings, the catch comprises an upper main body-portion 1 which is provided with 100 the usual loop-engaging and retaining lug or holder 2, said body-portion being also provided with any usual arrangement of nail or rivet-receiving holes or perforations,

as 3. The said catch also comprises a lower main body-portion 4 provided with any usual arrangement of nail or rivet-receiving holes or perforations, as 5.

5 Suitably secured in the proper location upon the outer face of said lower main body-portion 4, by means of fastening lugs or tongues 6, or other suitable fastening means, is a suitably formed box of sheet-metal, said 10 box comprising oppositely disposed sides 7, an inclined or angularly disposed front or face-member 8, and a closing top or end-portion 9, provided with an opening, as 10, for the reception of a lug-shaped portion 11, 15 extending from the upper main body-portion 1, when the parts of the catch are brought into their locked relation, substantially as illustrated in Fig. 4 of the drawings. The lower part of the box is left 20 open, as at 12, and the said inclined or angularly disposed front or face-member 8, terminates, as shown, along its lower edge, sufficiently above the lower marginal edges of the sides 7, so as to provide an open front 25 portion 13 and for the proper arrangement in said open portion 13 of a pair of perforated ears 14 which extend in forward directions from the said sides 7. Extending through the said ears 14 and laterally across 30 the said open portion 13 is a pintle 15 for pivotally mounting thereon, by means of an arrangement of pintle-receiving lugs or ears 17, a raising or lifting member or lever 16. This member or lever 16 is usually suitably 35 formed, as 18, so as to provide a fingerpiece for its proper manipulation, and between its lugs or ears 17, the said member or lever is provided with the usual spring-engaging element 19 adapted to extend rearwardly 40 into the space between the two sides 7 of the box, so as to forcibly engage the end-portion of a spring 20 which is secured by means of a rivet 21, or otherwise, to the lower body-portion 4, and all of which will be clearly 45 evident from an inspection of said Fig. 4 of the drawings.

Extending rearwardly from the marginal edge-portions of the said member or lever 16 are a pair of wings, as 22, preferably of 50 the configuration shown, and pivotally connected with the respective wings 22 are the inwardly extending pivot members or end-portions 24, see Fig. 1, of the usual holding or retaining loop 23, formed with the 55 usual yoke-portion 25 which can be disposed over the above-mentioned retaining lug or holder 2, by the proper manipulation of the said raising or lifting member or lever, as will be clearly understood from an 60 inspection of the several figures of the drawings.

It has been found in practice, in order to 65 obtain the proper clamping action of the yoke-shaped portion 25 with the engaging part 26 of the lug or holder 2, when the

parts are in their locked relation that the holding or retaining loop 23 must assume the position indicated in Figs. 2 and 4 of the drawings, and to accomplish this result, the means of pivotal connection of the lifting or raising means or lever 16 with the box of the lower main body-portion 4 must be located near the face of said body-portion, otherwise a loose fit between the yoke-shaped portion 25 and the retaining lug or holder 2 will be produced, thus rendering the catch practically useless. 70 75

Now, it has further been found in practice, that in the form of catches of the general construction, when made of sheet-metal, as brass, and when the face-member 8 of the box is made so as to be parallel with the face of the body-member 4, that such arrangement of the parts prevents the lifting lever 16, when raised, to be brought into its 80 properly rotated position, and that the operator in the manipulation of the lever usually forces the same with too great pressure against the face of the box, thereby 85 either straining, distorting, or breaking the 90 parts and thus rendering the catch inoperative.

With the inwardly inclined or angular disposition of the face-portion 8 of the box, the raised member or lifting lever 16 is 95 easily brought in contact with the entire face-portion 8 of the box, in the manner clearly shown in Fig. 3 of the drawings, which face-portion 8 of the box acts as a stop against further movement of the lifting or raising member or lever, and prevents any straining, distortion, or breaking of the thin sheet-metal members, as will be clearly 100 understood. 105

I claim:—

1. In combination, with a body-plate of a catch, a chambered box mounted upon said body-plate, said box having a face-portion in downwardly inclined relation toward the face of said body-plate, and an actuating lever pivotally connected with said box, said lever when raised being adapted to be brought into arrested engagement with the inclined face-portion of said box. 110 115

2. In combination, with a body-plate of a catch, stop means extending forwardly from said plate and having a face-portion in downwardly inclined relation toward the face of said body-plate, and an actuating lever pivotally connected with said stop-means, said lever when raised being adapted to be brought into arrested engagement with the inclined face-portion of said stop-means. 120 125

3. In combination, with a body-plate of a catch, stop-means extending forwardly from said plate and having a face-portion in downwardly inclined relation toward the face of said body-plate, an actuating lever 130

pivottally connected with said stop-means, set forth above I have hereunto set my hand
said lever when raised being adapted to be this 28th day of January, 1920.
brought into arrested engagement with the
inclined face-portion of said stop-means,
5 and a yoke-shaped retaining loop pivottally
connected with said lever.

In testimony that I claim the invention

JOSEPH S. ISIDOR.
